CLAIM

The ornamental design for a mounting card for a cleaning pad for an autonomous floor cleaning robot, as shown and described.

DESCRIPTION

FIG. 1 is a top perspective view of a mounting card for a cleaning pad for an autonomous floor cleaning robot according to our design;

FIG. 2 is a top view thereof;

FIG. 3 is a bottom view thereof;

FIG. 4 is side view thereof;

FIG. 5 is an opposing side view thereof;

FIG. 6 is an end view thereof; and,

FIG. 7 is an opposing end view thereof.

The broken lines shown herein depict portions of the mounting card for a cleaning pad for an autonomous floor cleaning robot that form no part of the claimed design.

1 Claim, 5 Drawing Sheets
